US00D789745S

(12) **United States Design Patent** (10) **Patent No.:** **US D789,745 S**
(45) **Date of Patent:** **** Jun. 20, 2017**

(54) **BOTTLE**

(71) Applicants: **Karim Rashid**, New York, NY (US); **Derrick Paul Lawrence**, Burlington, VT (US); **Brian D Schumacher**, Lima, OH (US)

(72) Inventors: **Karim Rashid**, New York, NY (US); **Derrick Paul Lawrence**, Burlington, VT (US); **Brian D Schumacher**, Lima, OH (US)

(73) Assignee: **Seventh Generation Ventures, Inc.**, Burlington, VT (US)

(**) Term: **14 Years**

(21) Appl. No.: **29/517,575**

(22) Filed: **Feb. 13, 2015**

(51) LOC (10) Cl. **07-01**

CLAIM

The ornamental design for a bottle, as shown and described.

DESCRIPTION

FIG. 1 is a perspective view of a bottle showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The bottom of the bottle forms no part of the claimed design. The broken lines in the drawings depict portions of the bottle that form no part of the claimed design.
